UNITED STATES PATENT OFFICE.

ROY L. WOODARD, OF RICHBURG, NEW YORK.

WELL-DRILLING MACHINE.

No. 900,636.

Specification of Letters Patent.

Patented Oct. 6, 1908.

Original application filed November 15, 1906, Serial No. 343,600. Divided and this application filed December 13, 1907.
Serial No. 406,340.

To all whom it may concern:

Be it known that I, Roy L. Woodard, a citizen of the United States, residing at Richburg, in the county of Allegany and State of New York, have invented a new and useful Well-Drilling Machine, of which the following is a specification.

This invention relates to machines for drilling wells and is a division of an application filed by me on November 18, 1906, and constituting the subject matter of Patent No. 861,928, granted to me on July 30, 1907.

The object of the invention is to provide a machine of this character which can be readily set up at the point of use and which is durable and compact in construction.

A still further object is to provide such a machine having means whereby long pipes, drills, etc. can be brought into position to be lowered into a well.

With these and other objects in view the invention consists of certain novel features of construction and combinations of parts which will be hereinafter more fully described and pointed out in the claims.

In the accompanying drawings is shown the preferred form of the invention.

In said drawings: Figure 1 is a side elevation of a well drilling machine embodying the present improvements. Fig. 2 is a plan view thereof, the derrick being removed adjacent the base thereof. Fig. 3 is an end elevation of the machine the upper portion of the derrick being removed. Fig. 4 is a side elevation showing the positions of certain of the parts during the operation of positioning a tool upon the machine.

Referring to the figures by characters of reference, A is the base frame of the machine made up of mud sills 1, 2, 3 and 4 on which are arranged longitudinal beams 5, 6 and 7, the sills 1, 2 and 3 being disposed below a platform 8. Disposed upon the sills 2, 3 and 4 and close to the beam 6 are parallel beams 9, 45 and 10 upon one end portion of which is mounted a jack post 11 having a cap 12 thereon from which retaining rods 13 extend downward to a holding plate 14 which is disposed beneath the sill 4. Another jack post 15 of similar construction is mounted above the sill 4 and the beam 5 and journaled upon the two jack posts and retained

thereon by the caps 12 is a shaft 16 carrying a crank 17 at one end of which is located a wrist pin 18.

An inclined support 19 extends rearwardly from the beam 9 and is suitably braced as shown at 20, said brace extending backward to the jack post 11. Another inclined support 21 extends rearwardly from the beam 5 and connected thereto is a brace 22 which is secured to the jack post 15 and extends across the support 21, there being a lever 23 pivotally connected to the lower end of said brace 22. Journaled within this lever and within the upper end of the support 19 are the trunnions 24 of a drum 25 and secured to this drum is a sand reel 26. An operating lever 27 is mounted at a suitable point upon the platform 8 and is connected to the upper end of the lever 23 by means of a rod 28 so that when the lever 27 is swung in one direction the drum 25 is shifted so as to swing the sand reel forward or backward.

Mounted on the beams 9 and 10 and above the sill 3 is a samson post 29 having inclined braces 30 and 31 secured thereto and to the beams 9 and 10 there being a rod 32 upon the upper face of the brace 31 which is bolted or otherwise secured to one of the beams 9 and 10 and to the upper portion of the samson post. Side plates 33 are fastened to the upper portion of the samson post and support a saddle 34 which is secured to the central portion of a walking beam 35. A stirrup 36 is arranged upon one end of the walking beam and is connected to a rod 37 which is provided adjacent its lower end with a slot 38 through which the wrist pin 18 extends. A post 39 is mounted upon the frame A close to the samson post and is connected thereto by means of braces 40 and rods 41. A band wheel 42 is secured upon the shaft 16 and disposed at one side thereof and rotatable therewith is a double tug pulley 43. The band wheel is adapted to receive power from a belt 44 or in any other suitable manner. A brake band 45 partly surrounds the sand reel and is secured at its ends to the jack posts 11 and 15 by means of rods 46. By shifting the sand reel in one direction by means of the levers 23 and 27 it will be forced against the brake band 45.

and held against rotation and by shifting it a short distance in the opposite direction it will be brought into contact with the band wheel 42 and be rotated thereby. Side 5 braces 47 and 48 are disposed at one side of the samson post and are secured to the base frame A and these braces are similar to the braces 30 and 31 and a brace rod 49 similar to the rod 32 is disposed along the upper face 10 of the brace 48 and fastened to the base frame A and the samson post. By means of the two sets of braces which have been described the samson post is held rigidly in an upright position and will resist all ordinary 15 strains to which it will be subjected.

Arranged upon one end of the base frame A and preferably directly above the sill 1 is the derrick 50 upon the upper portion of which is journaled a crown pulley 52.

20 A drum 69 is journaled between the lower portions of the uprights 50 and carries a bull wheel 70 and a tug pulley 71 adapted to receive power from the pulley 43 through a belt or cable 72. The tool carrying cable 25 73 of the machine extends over the crown pulley 52 and is adapted to be wound on the drum.

The actuation of the sand reel will of course be fully understood from the foregoing description as will also that of the walking beam which is to be used for actuating the drill. The principal importance in the present case is attached to the construction of the apparatus whereby the same 35 can be readily assembled at the point of use. It will be noticed that all of the parts are secured together by bolts and that the number of parts is reduced to the minimum. In order that tubing, drills, etc. may be 40 conveniently brought on to the platform 8 a track 74 extends up to the platform from a point removed any desired distance from the machine and this track carries a truck 75 on which tubing may be conveyed into the apparatus. For instance if a very long and 45 heavy stem 76 is to be raised the rear or lower end is placed on the truck while the upper or front end is attached to the rope 73 and by pulling on this rope the front end of 50 the stem will be raised and the truck will ride inward on the track carrying the lower or rear end of the stem. There is nothing to prevent this gradual upward swinging of the stem as would be the case if a four- 55 cornered derrick were used. Should a portion of the well casing extend above the surface of the ground or should other obstructions be located about the well opening the apparatus can be readily moved away from 60 the well by disconnecting the sills 7 and 9 whereupon the machine can be moved side- wise. In order that the apparatus may be strengthened directly under the samson post

29 truss rods 3' are extended under the sill 3 and are secured to the ends of the beams 65 9 and 10, as shown in Fig. 1. Trusses 35' are also used upon the walking beam as shown in said figure. This post 39 is inclined as indicated and constitutes a stop to prevent beam 35 from moving downward 70 against the derrick and damaging the machine or injuring the operator should the pitman 37 give way or should the outer end of the beam 35 become loose from any other cause. 75

What is claimed is:

1. In a machine of the character described the combination with a base; of a band wheel supported above the base, a rotatable drum, means for transmitting rotary motion 80 from the band wheel to the drum, a track extending onto the base from a point beyond one end thereof, a tool carrying truck mounted upon the track, and flexible means secured to the drum for engagement with 85 a tool upon the truck to transmit motion from the drum to the truck.

2. In a machine of the character described the combination with a base frame consisting of mud sills, beams thereon, and truss 90 rods disposed beneath the beams and extending under one of the sills; of a samson post disposed above said last mentioned sill, a walking beam mounted upon the samson post, an inclined post adjacent the samson 95 post, connections between said posts, braces extending from the base frame to the samson post, reinforcing rods extending longitudinally of said braces and connections, a crank arm, a stirrup upon the walking beam, 100 and a rod connecting said stirrup with the crank arm.

3. In a machine of the character described the combination with a base frame; of a track extending onto the base frame from a point beyond one end thereof, a tool carrying truck mounted to travel upon the track, a derrick, a bull wheel, a drum revoluble therewith, and a cable carried by the derrick and connected to the drum, said cable being 105 disposed to be wound upon the drum and to be secured to a tool upon the truck to actuate the truck.

4. In a machine of the character described the combination with a base frame consisting of mud sills, beams thereon, and truss rods disposed beneath the beams and extending under one of the sills; of a samson post disposed upon that sill extending over the truss rods, a walking beam mounted upon the samson post, a crank arm, a stirrup upon the walking beam, and a rod connecting the stirrup and crank arm. 110

5. In a machine of the character described the combination with a base frame consisting of mud sills, beams thereon, and truss 115 rods disposed beneath the beams and extending under one of the sills; of a samson post disposed upon that sill extending over the truss rods, a walking beam mounted upon the samson post, a crank arm, a stirrup upon the walking beam, and a rod connecting the stirrup and crank arm. 120

6. In a machine of the character described the combination with a base frame consisting of mud sills, beams thereon, and truss 125 rods disposed beneath the beams and extending under one of the sills; of a samson post disposed upon that sill extending over the truss rods, a walking beam mounted upon the samson post, a crank arm, a stirrup upon the walking beam, and a rod connecting the stirrup and crank arm.

rods disposed beneath the beams and extending under one of the sills; of a samson post disposed upon that sill extending over the truss rods, a walking beam mounted upon the samson post, braces extending from the base frame to the samson post, and reinforcing rods extending longitudinally of said braces.

In testimony that I claim the foregoing as my own, I have hereto affixed my signature in the presence of two witnesses.

ROY L. WOODARD.
